CLAIM

The ornamental design for a pet bed, as shown and described.

DESCRIPTION

FIG. 1 is a perspective view of the present invention;

FIG. 2 is a front view of the present invention;

FIG. 3 is a right side view of the present invention, the left side view being a mirror image thereof;

FIG. 4 is a back side view of the present invention;

FIG. 5 is a top view of the present invention; and,

FIG. 6 is a bottom view of the present invention.

The broken lines in FIG. 6 immediately adjacent the shaded areas or the solid lines represent the bounds of the claim, and the broken lines and the area within the broken lines represent unclaimed portions of the present invention. None of the broken lines form a part of the claimed design.
